(57) **CLAIM**

The ornamental design for a training device for stick based sports, as shown and described.

DESCRIPTION

FIG. 1 is a top perspective view of a training device for stick-based sports;

FIG. 2 is a bottom perspective view thereof;

FIG. 3 is a front view thereof;

FIG. 4 is a back view thereof;

FIG. 5 is a left side view thereof;

FIG. 6 is a right view thereof;

FIG. 7 is a top view thereof;

FIG. 8 is a bottom view thereof;

FIG. 9 is a top perspective view of a second embodiment of a training device for stick-based sports;

FIG. 10 is a bottom perspective view thereof;

FIG. 11 is a front view thereof;

FIG. 12 is a back view thereof;

FIG. 13 is a left side view thereof;

FIG. 14 is a right view thereof;

FIG. 15 is a top view thereof; and,

FIG. 16 is a bottom view thereof.

The broken line showing of the training device for stick-based sports is included for the purpose of illustrating portions of the article and forms no part of the claimed design.

1 Claim, 10 Drawing Sheets
